UNITED STATES PATENT OFFICE.

RUSSELL W. CAMFIELD, OF BERKELEY, AND ERNEST G. DANIELSON, OF SAN FRANCISCO, CALIFORNIA.

VARIOMETER.

Application filed February 7, 1923. Serial No. 617,458.

To all whom it may concern:

Be it known that we, RUSSELL W. CAMFIELD, a citizen of the United States, and a resident of the city of Berkeley, in the county 5 of Alameda and State of California, and ERNEST G. DANIELSON, a citizen of the United States, and a resident of the city and county of San Francisco, in the State of California, have invented a new and useful 10 Variometer, of which the following is a specification.

This invention relates to an inductance coil having relatively movable coil portions, whereby the total inductance of the coil may 15 be varied. Such an instrumentality is usually termed a variometer and is extensively used in connection with radio signaling.

It is one of the object of our invention to improve in general the mechanical features 20 of such a device whereby it may be more reliable in service and neater in appearance.

Variometers are usually provided with two substantially equal coils concentrically disposed and connected in series, that are 25 relatively rotatable so that they may gradually be adjusted from a position where they are cumulative to the maximum degree, to one where they oppose each other to a maximum degree. This movement is rendered possible 30 by providing an axis of rotation for the rotor coil substantially at right angles to the axis of both coil windings. The connections for the circuit must of course be provided between the rotor coil and the stator coil, but 35 as hitherto arranged these connections have had disadvantages, such as being the cause of interfering noises, or else they were liable to work loose or break off. It is thus another object of our invention to provide an improved form of circuit connection between 40 the relatively movable coils.

Our invention possesses other advantageous features, some of which with the foregoing, will be set forth at length in the following description, where we shall outline in full that form of the invention which we have selected for illustration in the drawings accompanying and forming part of the present specification. Although we have shown 45 in the drawings but one embodiment of our invention, we do not desire to be limited thereto, since the invention as expressed in the claims may be embodied in other forms 50 also.

Referring to the drawings:

55

Figure 1 is a front view of a variometer embodying our invention;

Fig. 2 is a view taken from the right hand side of Fig. 1 with rotor turned 30°;

Fig. 3 is a view of the variometer taken 60 apart, with the rotor and stator elements opened up along a plane perpendicular to the axis of rotation of the rotor, and with certain other elements displaced slightly so as to show the construction of the parts in 65 a clear manner;

Fig. 4 is a sectional view taken along plane 4—4 of Fig. 3; and

Fig. 5 is a sectional view taken along plane 5—5 of Fig. 3. 70

The stator coil 11 is in the present instance arranged external to the rotor coil 12, and is furthermore wound so as to provide substantially an internal spherical surface within which the spherically formed 75 rotor coil 12 may rotate, with a relatively small amount of clearance. In order to support this stator coil properly, we provide a pair of supports 13, preferably molded from insulating material. On the interior 80 surfaces of these supports 13 the stator coil sections 11 are appropriately fastened, as by glue or the like, there being one coil section 11 for each of the supports 13. Projections 14, 15 from the sides of supports 13 85 serve conveniently not only to embrace the metal spacers 16, 17 but also to provide an anchor for the feet 18, upon which the entire variometer may rest. Bolts 19 serve to fasten the spacers 16, 17, the supports 13 and the 90 feet 18 securely together. The two stator coil sections 11, as well as the supports 13, are in this way kept a slight distance apart in an axial direction, this separation corresponding to the thickness of the spacers 95 16, 17.

These spacers are in fact provided primarily for keeping the stator sections separated, whereby it is possible to provide appropriate shafts for the rotation of the rotor coil 12. This coil 12 is likewise formed of two sections, wound on the rotor frames 20 that are preferably molded from insulating material. These frames 20 are adapted to be fastened together, as by bolts 21, that pass 100 through the integrally formed end covers 22 of the frames 20. Thus these frames 20 105 form a drum shaped figure with a spherical

outside surface, and covers 22 corresponding to the heads of the drum. The rotor coil sections 12 are wound on the outer periphery of this drum, and are adapted, by proper rotation of the drum, to cooperate with the stator coils 11 for varying the total inductance of the device. The axis of rotation for the rotor 12 passes through the center of spacers 16 and 17 as well as through the center of the stator and rotor coils. Rotation of 180° of the rotor about this axis would change the inductance from a maximum to a minimum.

To the spacer 17 is rigidly fastened a shaft or pivot 23, which for this purpose is provided with a shoulder 24 and a stud portion 25 projecting through the spacer. A nut 26 serves to clamp the shaft 23 securely to this spacer. It is upon this shaft that the rotor structure 12 is rotatably supported at one side. For this purpose, the rotor frames 20 are each provided with half-round depressions 27 which serve to embrace shaft 23 when the two frames are fastened together. The shaft 23 furthermore serves to accommodate the connections between the rotor and stator in a neat and compact manner, and in order to accomplish this result, the shaft is provided with an axial aperture 28, as well as a radial aperture 29 communicating therewith. The entire scheme of connections is apparent from a consideration of Fig. 3. That stator coil 11 which is associated with the lower frame 13 in Fig. 3, is connected, by a flexible lead 30, to the outside diameter of shaft 23, with the aid of a drop of solder. This connection is made close to the spacer 17, so that it may not interfere with the free rotation of the rotor 12 about shaft 23. Continuing with the connections, a flexible lead or pigtail 31 is soldered to the shaft 23 where it projects into the hollow drum formed by members 20. This connection leads to one of the rotor coils 12, which is connected, as by flexible lead 32, with the other rotor coil. The insulated flexible lead 33 from this rotor coil is threaded through apertures 28 and 29 of shaft 23, and connects to that stator coil 11 which is associated with the upper frame 13 of Fig. 3. From the foregoing, it is evident that all of the stator and rotor coil sections are in series, each of the two stator coil sections being disposed at the ends, and both of the rotor coils being arranged between these two stator sections. Leads 34 and 35 from the stator coils may connect to appropriate binding posts 36 whereby the variometer may be placed in any desired circuit.

It is to be noted that the pigtail connections 31 and 33 from the rotor coil are disposed within the hollow supporting frame formed by sections 20, and are completely hidden from view. Furthermore the move-

ment of the rotor about the pivot 23 results merely in a slight twisting of some of the leads, and there are no rubbing or wiping metallic contacts of any kind. For this reason there can be no objectionable noises produced during adjustment, in case the variometer is used in receiving circuits. It is further to be noted that the leads 31 and 33 cannot be adversely affected by the turning of rotor 22, since they have a length of considerable extent over which the angular twist is distributed. This effect is due in a measure to the arrangement of these leads in the hollow pin 25; the lead 33 passing through the stationary radial aperture 29 conveniently located in the gap formed between the spacer 17 and the outside surface of rotor 22; and lead 31 being anchored as by solder near the inner extremity of pin 25.

If no limit be placed upon the relative angular movement between rotor and stator, there would be danger of the leads finally twisting off. In order to insure against such an occurrence, we provide a stop that is incorporated with the shaft 37 which is fastened to the rotor axially in line with shaft 23 and on the opposite side thereof. This shaft is appropriately journaled in the spacer 16, and is held within the frames 20 of the rotor against relative rotation therewith, as by the aid of a pin 38 passing through the shaft and fitting into the depressions 39 formed for it in these frames. The projecting end 40 of the shaft 37 serves as a convenient means for adjusting the position of the rotor. The stop for the rotor comprises a pin 41 fastened to shaft 37, and arranged to play in a groove 42 formed in the projection 14 of only one of the stator frames 13. The pin 41 therefore permits only about 180° of movement of the shaft 37, for beyond that value this pin abuts against that portion of the inner wall of a projection 14 which falls opposite the groove 42. In this way a slot or groove is formed that extends only for a limited angle within which the stop pin 41 may play.

We arrange matters in such a way as to prevent relative axial movement between the pivot shaft 23 and the rotor frame, as well as to provide for a slight frictional resistance to the turning of the rotor, whereby it may be maintained in an adjusted position. For this purpose a groove 43 is cut in the shaft 23, with which cooperate one or more leaf springs 44, shown most clearly in Fig. 4. These springs are conveniently disposed in pockets 45 formed in the frames 20, and press resiliently against the groove 43. The shoulders 46 of the groove prevent relative axial movement between the springs 44 and the shaft 23, and at the same time sufficient frictional force is developed between the springs and the shaft to maintain the rotor in any adjusted position.

We claim:

1. In a variable inductor, a stationary coil structure, a rotatable coil structure within the stationary structure, and means for rotatably supporting said rotatable coil and for leading connections thereto, comprising a hollow pivot pin for said rotatable coil, fastened to the stationary coil and projecting radially inwardly into the rotating structure, said pin having an aperture communicating with the interior hollow space, and opening to the space formed between the rotary structure and the stationary structure, and a lead from one terminal of the rotary coil passing through the hollow pin and said aperture.
2. In a variable inductor, a pair of hollow shells, spacers between said shells, said shells serving to define an interior spherical surface, a stationary coil supported on said surface, a rotary coil structure within the shell, and means for rotatably supporting said rotatable coil and for leading connections thereto, comprising a hollow pivot pin fastened to one of the spacers and extending inwardly into the rotary structure, said pin having an aperture communicating with the interior hollow space, and opening to the space formed between the spacer and the rotary structure, and a lead from one terminal of the rotary coil, passing through the hollow pin and said aperture.

3. In combination, a stationary structure, a rotatable coil structure, a pivot pin fastened to one of the structures and relatively rotatable with the other, and a flat spring carried by the structure that is rotatable on the pin for producing a frictional resistance to relative movement of the two structures.
4. In combination, a stationary structure, a rotatable coil structure, a pivot pin fastened to one of said structures and relatively rotatable with the other, said pin having a groove formed therein, and a flat spring fitting within the groove, carried by the structure within which the pin has relative movement, whereby a frictional resistance is produced against relative movement of the two structures.
5. In combination, a stationary structure, a pivot pin fastened to said structure, a rotatable coil structure pivoted on said pin and formed of separable frames which are adapted to embrace the pin, said pin having a groove formed therein, and a resilient member held in a pocket between the separable frames for contacting with the groove, whereby a frictional resistance is produced against relative movement of the two structures.

In testimony whereof, we have hereunto set our hands.

RUSSELL W. CAMFIELD.
E. G. DANIELSON.
